CLAIM

The ornamental design for a tablet case with keyboard, as shown and described.

DESCRIPTION

FIG. 1 is a front elevation view of a tablet case with keyboard showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an exploded front elevation view of the tablet case with keyboard;

FIG. 10 is a rear elevation view thereof;

FIG. 11 is a perspective view thereof; and,

FIG. 12 is an enlarged view of the encircled portion in FIG. 7.

The dash-dot-dash lines in FIG. 7 and FIG. 12 illustrate the enlarged view indicators and form no part of the claimed design.
